United States Patent Office.

HARRISON SMITH, OF SANDYVILLE, AND JOHN H. EVANS, OF BOLIVAR, OHIO.

Letters Patent No. 91,571, dated June 22, 1869.

IMPROVEMENT IN HORSESHOES.

The Schedule referred to in these Letters Patent and making part of the same.

To all whom it may concern:

Be it known that we, HARRISON SMITH, of Sandyville, and JOHN H. EVANS, of Bolivar, both in the county of Tuscarawas, and State of Ohio, have invented new and useful Improvements in Horseshoes; and we do hereby declare that the following is a full, clear, and exact description of our invention, reference being had to the accompanying drawings, forming a part of this specification, and the letters of reference marked thereon, of which drawings—

Figure 1 is a plan of our improved horseshoe, with calks turned upward.

Figure 2 is an elevation of the same.

Figure 3 is an elevation, showing the principles of construction used in making our improved horseshoe.

Figures 4, 5, 6, 7, are elevations of the toe and heel-calks.

The nature of our invention consists in the construction of a horseshoe with two movable toe-calks and movable heel-calks; said calks having a stem with a right or left-handed thread cut thereon, by which they are secured in holes in the shoe; and the said calks being so arranged in the shoe, that the pulling or slipping of the horse shall cause the calks to tighten themselves in the shoe, whereby we avoid the use of any devices for holding the calks from unscrewing, which have been found necessary in shoes with movable calks, heretofore invented, to prevent the calks from working loose, whereby we lessen the cost and weight of the shoe, and greatly increase its utility.

To enable others skilled in the art to make and use our invention, we will proceed to describe its construction and operation.

The shoe A is of the ordinary form, with holes *a a*, through which pass the nails by which it is secured to the horse's foot, and grooves *f f*, for the heads of said nails.

The toe-calks, B and C, are two in number, and are secured to the shoe A by means of the stems *b* and *c*, which screw into holes in the shoe A.

The heel-calks D and E are secured to the shoe A by the stems *d* and *e* in a similar manner.

The screw-thread on the stem *b* of the toe-calk B is a right-handed thread, while that on the stem *c* of the other toe-calk C, is a left-handed thread.

The thread on the stem *d* of the heel-calk D, which is behind the toe-calk B, is a left-handed thread, while that on the stem *e* of the other heel-calk E is a right-handed thread.

It is readily seen that all the calks in the shoe are screwed into place, and tightened by turning the calks

towards the centre of the shoe, as indicated by arrows in fig. 1.

When a horse has to draw a load, he will either draw on the two toe-calks or on the four calks together, the first case being where the heel-calks have no bearing, and the second case being where a firm bearing is had by the whole shoe.

In the first case the toe-calks, if they move at all, will tend to tighten themselves in the shoe A, and in the second case, as the whole shoe has a square bearing, there is no danger of any of the calks moving in the shoe.

The same tightening of the toe-calks must ensue from a drawing of the horse on one toe-calk, as in this case the outer edge of the calk is the one acted on, as seen in fig. 3, where the shoe is inclined, the arrow *H* representing the direction of the force applied to the shoe by the drawing of the horse, and the arrow *k*, the direction of the force applied to the toe-calk B.

In case the horse has to hold back a load, as in going down-hill, he will either hold on the whole shoe or on the heel-calks only.

In the first case there will be no danger of the calks working loose, and in the second case, as the outer edge of heel-calk is the edge to take the bearing, the tendency is to tighten the calk, as seen in fig. 3, where the arrows *K* represent the direction of the force applied to the shoe by the holding back of the horse, and the arrows *k*, the direction of the force applied to the calk D.

The same explanation will apply to the slipping of the horse on the side of the foot, from which it is readily seen that no extra device is required to insure the calks from working loose.

Having thus fully described our invention,

What we claim as our invention, and desire to secure by Letters Patent, is—

A horseshoe, composed of the shoe A, toe-calks B and C, and heel-calks D E, with stems *b c* and *d e*, having right or left-handed threads cut on each, respectively, as herein shown, the several parts being arranged and combined substantially in the manner and for the purpose herein specified.

As evidence that we claim the foregoing, we have hereunto set our hands, in the presence of two witnesses, this day of , A. D. 1868.

HARRISON SMITH.
JOHN H. EVANS.
